Primary Examiner — Katie Jane Stofko(74) *Attorney, Agent, or Firm* — Troutman Sanders, LLP; Christopher C. Close, Jr.(57) **CLAIM**

I claim the ornamental design for a chick cake, as shown and described.

DESCRIPTION

FIG. 1 is a top, front, right perspective view of a first embodiment of a chick cake;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, front, right perspective view of a second embodiment of a chick cake;

FIG. 9 is a front elevation view thereof;

FIG. 10 is a rear elevation view thereof;

FIG. 11 is a left side elevation view thereof;

FIG. 12 is a right side elevation view thereof;

FIG. 13 is a top plan view thereof; and,

FIG. 14 is a bottom plan view thereof.
